UNITED STATES PATENT OFFICE.

K. H. C. PRESTON, OF MANLIUS, NEW YORK, ASSIGNOR TO E. P. RUSSELL,
OF SAME PLACE.

IMPROVEMENT IN HARVESTERS.

Specification forming part of Letters Patent No. **33,975**, dated December 17, 1861.

To all whom it may concern:

Be it known that I, KING H. C. PRESTON, of Manlius, in the county of Onondaga and State of New York, have invented a new and useful Improvement in Harvesters; and I do hereby declare that the following is a full and exact description thereof, reference being had to the accompanying drawing, which forms a part of this specification.

My improvement in harvesters consists in transmitting the requisite rate and force of motion from the driving-wheel A to the crank-shaft C through the medium of the series of rollers e e which are pivoted to the face of the said driving-wheel, and the tapering single screw-thread d, which projects from the periphery of the said crank-shaft.

By employing but a single screw-thread upon the crank-shaft C for the aforesaid series of rollers e e to act upon, and by giving the said screw-thread a gradually-tapering shape, I am enabled to place the crank-shaft in such a position that its axis will be exactly opposite to a portion of an imaginary circular line passing through the centers of the pivots of each of the rollers e e, and I am also enabled to place the said rollers in such near proximity to each other that an unusually-smooth movement is imparted to the crank-shaft, and everything like "backlash" in the working of the said screw-thread d and the rollers e e is entirely prevented. If the screw-thread d were of uniform thickness from end to end, the rollers e e would have to be placed at a much greater distance from each other, and consequently a great amount of backlash would be the result.

The position of the crank-shaft with relation to the pivots of the series of rollers e e, before referred to, enables me to act upon the thread d of the crank-shaft by means of rollers, instead of oval-headed pins, as is the case in the "Haviland harvester," and the said position

of the crank-shaft in my machine also enables me to use rollers e e which have tapering bearing-peripheries of substantially the shape represented in the drawings.

The tapering screw-thread d I shall generally cast in one piece with a tube, B, and then fit the said tube to the crank-shaft in such a manner that it will only carry the said shaft around with it when it is rotated by means of the forward movement of the driving-wheel A. The tapering shape of the screw-thread d enables the pattern of the thread-bearing tube B to be easily drawn from the sand during the process of molding the same preparatory to casting.

What I claim as my invention, and desire to secure by Letters Patent, is—

1. The tapering shape of the single screw-thread d, which I employ for the purpose of enabling the desired amount of motion to be communicated to the crank-shaft C, substantially as herein set forth.

2. When a tapering single screw-thread is combined with a shaft, either directly or through the medium of a tube or collar, I also claim acting upon said screw-thread by means of a series of pivoted rollers and a driving-wheel for carrying the same, substantially as set forth.

3. When a tapering single screw-thread is combined with a shaft, either directly or through the medium of a tube or collar, I also claim acting upon the said screw-thread through the medium of a series of tapering pivoted rollers and a suitable driving-wheel, substantially in the manner herein set forth.

The above specification of my improvement in harvesters signed by me this 7th day of September, 1861.

K. H. C. PRESTON.
